D. Rittenberg
Attorney.

UNITED STATES PATENT OFFICE.

JOHN J. LANGMACK, OF PORTLAND, OREGON.

AUTOMATIC OIL PUMP WITH SIGHT FEED.

Application filed September 24, 1925, Serial No. 58,413. Renewed August 19, 1927.

My invention relates to sight feed oil pumps of the character shown and described in my Letters Patent No. 1,343,677, issued June 15, 1920, and has among its principal objects to provide a construction in which the discharge is through the bottom of the box or casing, and in which there are new and improved regulating and controlling features, and other refinements and improvements which make for greater efficiency and certainty in operation.

In order to explain my invention, I have shown the same on the accompanying two sheets of drawings, which I will now describe.

Figure I is a top plan view with cover removed and other parts shown in section;

Figure II is a vertical sectional view taken on line II—II of Fig. I;

Figure III is a cross sectional view taken on line III—III of Fig. I;

Figures IV and V are enlarged face and edge views of a spring spider for feed adjustment;

Figures VI and VII are similar views of a lock ring for the same;

Figure VIII is a front view of crank disk;

Figure IX is detail of crank shaft;

Figure X is detail of ratchet wheel therefor;

Figure XI is detail of eccentric cam for said shaft;

Figure XII is a longitudinal sectional view of a double check valve;

Figure XIII is an end view of the same; and

Figure XIV is a vertical sectional view through the lower end of a suction leg.

Referring now in detail to the drawings, 1, designates a box or case having the floor flanges, 2, 2, for securing it upon a suitable support, and provided in the upper edges of the opposite end walls and the opposite side walls with bearing openings, as, 3, 3, and 4, 4, forming saddles for the members, 5, 5, and 6, 6, in the end walls and the members 7 and 8, in the side walls, which members are again referred to.

The members 5, 5, are alike and each constitutes a pump and check valve, having a cylinder, 5^a, formed therein, a cylindrical chamber, 5^b, connected with the cylinder by a passageway, 5^c, and being closed at its outer end by means of a screw plug, 5^d. A cylindrical valve body, 9, fits in said cylin-

drical chamber 5^b, with two valve seats 10, 10, therein, with spring held valves, 11, 11, inserted through the top of the member 5, as clearly indicated in Fig. II. Said valve body, 9, has a passageway therethrough from the passageway, 5^c, to the outlet pipe, 12, extended down through the bottom of the box 1, as at 13, where it is provided with a nut, 14, to hold it in place. Said pipe, 12, is placed inside a pipe or sleeve, 15, screwed into the bottom of the box, as shown.

The members, 5, 5, are formed as parts of vertical members, 16, 16, Fig. III, each provided with a drip port, as 17, leading down into the cylinder 5^a, as indicated by the sectional part in Fig. III. Said vertical members, 16, 16, are each provided with longitudinally extending passageway, as 18, communicating at their upper ends with a spout, 19, and at their lower ends, with a chamber, 20, in which is a ball valve, 21, normally held by means of a spring, 22, and screw plug, 23, as seen in Fig. XIV. In the lower end of each of said members, 16, is formed a cylinder, as 24, the outlet to which is controlled by said ball valve, 21. Inlet to said cylinder is through the lower end of the member 16, which is provided with an open screw plug, 25, with ball valve therein, as 26, said screw plug having a screen, 27, in its bottom, as indicated. Thus the lubricant in the box or case, 1, is drawn through said screen plug 25, into the cylinder, 24, and is forced out through the passage 18 and the spout 19, in a manner again herein referred to. From the spout the oil or lubricant drops into the member 16, and its passageway, 17, and runs down into the cylinder, 5^a, from which it is forced out through the passage 5^c, through the cylindrical valve member 9, and to the feed pipe, 12, extending out through the bottom of the box or case.

I will now describe the mechanism for operating the pistons in said cylinders, 5^a and 100 24, and referring particularly to Figs. I and II.

The bearing members 7 and 8, in the opposite side walls of the box 1, carry a shaft 28, octagon for a part of its length, as at 28^a, Fig. IX. On said shaft are mounted two eccentric cam discs, as 29, 29, with spacing sleeves, 30, 31, and 32. Each of said eccentric cams, 29, operates a yoke, as 33, having connected to one side thereof, a piston, as 110

34, which operates in the cylinder, 5^a, in the member 5, before referred to. The other side of each yoke, 33, is connected with a regulating screw, 35, having its outer end hexagonal in form and telescoping into an adjustment nut, 35^a through the member 6.

The members, 16, 16, have the web portions, as 16', and each has an extension arm, 16^a, on the outer end of which is pivoted 10 a rocker arm, 36, the lower end of which is connected by means of a slotted head, 37, with a piston, 38, which works in cylinder 24, before referred to. The upper end of the rocker arm, 36, in each case, is connected 15 by means of a slotted screw head, 39, with said adjustment screw 35, whereby said parts can be adjusted for regulation of the pumping action of the pistons 34 and 38. A spring spider, 40, is placed on the inner end 20 of the adjustment nut 35^a, with a spring ring, 41, around the inner end of said adjustment nut 35^a, for holding said adjustment nut in its different adjustment positions. The spring spider bears against the member 6, as clearly shown, and thus yieldingly holds the adjustment nut, which, when turned, turns the adjustment screw 35, to move the screw head, 39, on the screw.

Mounted on said shaft 28, within the box 30 1, is an operating ratchet wheel, 42, operated by two pawls, 43 and 44, pivotally connected with a yoke member, 45, on the hub portion 46, of a wheel, 47, on the outer end of said shaft 28, as clearly seen in Fig. 1. A folding crank, 48, is pivotally connected on the outer face of said wheel, 47, and is adapted to fold into closed position, as indicated in solid lines, or to open out for hand operation, as indicated in light broken lines. A 40 spring, 49, holds it in either position of adjustment, as will be clear from the showing thereof. Depending from the lower side of said wheel 47, is an operating rod, 50, which is detachably screwed into the rim of said wheel, as indicated, with its lower end extended down to be connected, as by means of a member, 51, to an operating rod, 52, which can be connected with any moving part of the machinery to be lubricated. Thus the oscillating of said rod 50, through the wheel 47, operates the ratchet wheel 42, on the octagonal shaft 28^a, and through said shaft operates the two eccentric cam disks, 29, 29, and through the yokes, 33, 33, and their connections, operate the pistons, 34 and 38, for drawing in the lubricant from the box, 1, into cylinders, 24, 24, and forcing it through passageways, 18, 18, in the vertical members 16, 16, the spouts, 19, 19, and to the cylinders 5^a, 5^a, from which it is forced through the valve members 9, 9, and to the outlet or feed pipes, 12, 12, through the bottom of the box 1, as before described. Glass cups, 53, 53, are placed around the spouts, 19, 19, and a glass cover, 54, is secured to the removable

cover, 55, of the box or case 1. A hinged closure member, 56, covers a screened opening into the top of said cover 55, as indicated in Fig. II, for supplying lubricant to said box.

Figs. XIII and XIV are enlarged views of the construction of the double check valve member, through which the lubricant is forced, with the removable cylindrical valve body, 9, and the spring held valves, 11, this being similar to that shown in connection with the member 5, in Fig. II, and is similar to that shown in my former patent referred to and is not claimed in connection with this application.

One of the important features of the present invention is the provision of the sleeve or pipe 15, connected through the bottom of the box or case 1, and through which the discharge pipe leads. This enables me to remove the pumping mechanism from the box or reservoir without draining the lubricant therefrom, which in itself is of very great importance, for when it is necessary to drain the lubricant from the reservoir and make disconnections, it takes several hours and requires a shutting down of the engine, but with my construction a pumping unit can be taken out to be cleaned or repaired without removing the box or reservoir from the engine, and said pumping units can be removed without any mechanical operations whatever, for it will be clear from the construction shown and described that the entire pumping mechanism can be bodily lifted 100 from the box or case after removing the cover 55.

I do not limit the invention to the showing made for illustrative purposes, except as I may be limited by the hereto appended claims.

I claim:

1. In a device of the character referred to, a box, a pumping mechanism therein including a cylinder and piston and means providing a passageway through which lubricant from said box is pumped, said passageway including a spout and a gap across which said lubricant drops from said spout, a sleeve secured in the bottom of said box and extending upwardly above the lubricant level, and a feed pipe extending through said sleeve and through the bottom of said box and to which said lubricant is fed.

2. In a device of the character referred to, in combination, a box or reservoir for lubricant, a sleeve set in the bottom of said box and extending above the lubricant level, a pumping mechanism set into said box and including a circulating passageway having an open gap across which lubricant is pumped, whereby to furnish sight feed, and a discharge pipe into which said lubricant is pumped across said gap, said discharge pipe being extended through said

sleeve, whereby said pumping mechanism can be lifted bodily from said box without disconnecting said box.

3. In a sight feed pumping mechanism, a box, a sleeve set in the bottom thereof and extending above the level of lubricant placed therein, a pumping mechanism set into said box and adapted to pump lubricant from said box, a discharge pipe extended through said sleeve and connected with said pumping mechanism, said pumping mechanism including a gap across which said lubricant is pumped before reaching said discharge pipe, a transparent covering for said gap, where by the lubricant can be seen as it passes across said gap, and means whereby said pumping mechanism can be lifted bodily from said box without disconnecting the same or removing the lubricant therefrom.
- 20 4. In a device of the character referred to, a box having lubricant therein, a sleeve set in the bottom of said box and extending up into said box, a pumping mechanism therein, a spout through which said lubricant is pumped, a second pumping mechanism to which said lubricant is fed by a drop from said spout, a transparent cover around said gap, whereby said lubricant is visible as it drops from said spout, and a discharge pipe

through said sleeve and the bottom of said box through which said second pumping mechanism forces said lubricant for feeding to place of use.

5. An automatic oil pump with sight feed, including in combination, a box, a sleeve set in the bottom thereof and extending up into said box, a pumping mechanism removably set into said box and detachably connected with the sides thereof, said pumping mechanism including a discharge spout in the upper part of said box and a discharge pipe extending through said sleeve and adapted to receive lubricant from said spout, and a transparent cover around said spout to make visible the lubricant discharged therefrom.

25 6. A sight feed oil pump including in combination a container for oil, a sleeve set in the bottom of said container and extending upwardly above the oil level and providing an outlet through the bottom of said container, a pumping mechanism removably set in said container and having a discharge pipe extended through said sleeve, and means providing a sight feed of oil from the pumping mechanism to said sleeve.

Signed at Portland, Multnomah County, Oregon, this 14th day of September, 1925.

JOHN J. LANGMACK.
